UNITED STATES PATENT OFFICE.

DANIEL E. DAVISON, OF BROOKLYN, NEW YORK.

CLOTHESLINE BRACKET AND TRAY.

Application filed March 15, 1921. Serial No. 452,444.

To all whom it may concern:

Be it known that I, DANIEL E. DAVISON, a citizen of the United States, and a resident of the city of New York, borough of Brooklyn, county of Kings, and State of New York, have invented a new and Improved Clothesline Bracket and Tray, of which the following is a full, clear, and exact description.

This invention relates to an apparatus for supporting a clothes line in such a manner that one end may be moved into a room through a window when applying or removing clothes and may be moved to a position exterior of the window when not in immediate use.

Another object of the invention is to provide a simple, strong construction which may be cheaply manufactured and easily operated to support a clothes line with a section extending through the window or held interiorly thereof as desired.

In the accompanying drawings—

Figure 1 is a perspective view illustrating one embodiment of the invention in connection with a window.

Figure 2 is a longitudinal vertical section through the clothes support or tray shown in Figure 1.

Figure 3 is a top plan view of the bracket shown in Figure 1 with certain parts broken away.

Figure 4 is an elevation of the structure shown in Figure 3, certain parts being broken away.

Referring to the accompanying drawing by numerals, 1 indicates a window frame which may be of any desired construction and 2 a lower window sash which is shown in the drawing as having been raised to provide a window opening 3. In many cities and other places it is customary to provide a clothes pole in the yard or some convenient point and support endless pulley lines on the pole and on the frame 1. Where this is done the person using the line must reach through the window opening 3 in order to reach the line to hang articles thereon.

In the present invention a bracket has been provided whereby one end section of the line may be caused to extend through the window opening 3 whereby clothes may be hung thereon without reaching through the window opening 3. As illustrated in the drawing a supporting bracket 4 is

screwed or otherwise rigidly secured to the frame 1 and has a shaft or bar 5 rigidly secured thereto by a nut or other securing means. The shaft 5 is clamped rigidly to the support 4 and held against rotation by the clamping action or in any suitable manner. A sleeve 6 is rigidly secured in any desired manner to the shaft, said sleeve having an elongated casing 7 in which guiding pulleys 8 and 9 are mounted, said pulleys being held in their journals arranged substantially vertical whereby the upper section 11 of the clothes line 12 is guided in its movement whether parallel to or at an angle through the arm 13. The shaft 5 is provided with a pair of locking pins 14 and 15 spaced apart a sufficient distance to permit the arm sleeve 16 to freely rotate when centrally located between these pins. The arm sleeve 16 is provided with slots 17 and 18 arranged at right angles to each other, said slots being of a size to accommodate the respective pins 14 and 15. When the arm is positioned within the room as shown in Figure 1, the sleeve 16 is pushed over until the pin 15 is located in the slot 18. This will lock the arm 13 against any swinging movement. When it is desired to swing the arm to an outer position, sleeve 16 is slidably moved along shaft 5 until it is disengaged from the pin 15 and then rotated through approximately 90° and then slid over until pin 14 is in slot 17 whereupon the arm will be locked in a substantially vertical position.

The inner end of the arm 13 is provided with a knob 19 which carries a bolt 20, which bolt in turn supports a hook 21. A pulley 22 of any ordinary or desired kind is removably connected with the hook 21 and acts as the inner pulley wheel for the line 12. The outer pulley wheel is not shown in the drawing but is of any desired kind and is mounted on the usual supporting post now in common use. The lower section 23 of the line 12 naturally sags down as shown in Figure 1 and is in ready position for receiving the clothes. When an article has been placed on this section it is forced outwardly through the window opening 3 and section 11 automatically feeds in. When the line has been filled and it is desired to close the window section 23 is passed over one of the hooks 24 or 25 as shown in dotted lines in Figure 1 and then arm 13 swung to its outer position as here-

tofore described. By looping the section 23 over either of the hooks 24 and 25, the line is maintained taut after the arm 13 has been moved to its outer position.

5 When connecting the clothes with section 23 and line 12 it is necessary to either support the clothes by the hand or by some other means. When a large article, as for instance, sheets, is to be hung on the line 10 a tray 26 is provided in which these articles may be placed and merely their upper edges raised to the section 23 and fastened thereon. As the articles are fastened on this section, 15 said section is gradually moved out and, consequently, the article will gradually move over the roller 27 and eventually swing free in the air. The tray 26 is provided with a 20 pair of side members 28 and 29 and a bottom member 30 which is supplied with plates 31 and 32 adapted to straddle either all or part of the window frame 1 whereby it is prevented from sliding. A supporting rod 33 is pivotally mounted in the side members 28 and 29 and provided with 25 a hook end 34 adapted to hook over the knob 19 so that the inner end of the tray may be properly supported. A division plate 35 and a hinged lid 36 is arranged adjacent the inner end of the tray and 30 these members in connection with the side

members 28 and 29 and the end 37 form a compartment for clothes pins or any desired article.

What I claim is:—

1. A clothes line support, comprising a 35 bar carrying a securing bracket at one end and a pair of line rollers at the other, a pair of spaced pins extending crosswise through said bar at points between the bracket and the rollers, a rotatable sleeve 40 slidably mounted between said pins, said sleeve carrying an arm, said sleeve having slots at both ends to engage either of said pins and so disposed that the sleeve is rendered capable of being locked against movement at every quarter turn.

2. A clothes line support including a member adapted to be secured to a window frame, a bar having a plurality of spaced pins adjacent the center thereof secured to 50 said member, a sleeve carrying a pair of line rollers and a hook member secured to the free end of said bar, a rotatable sleeve between said pins carrying an arm, said sleeve being slotted at both ends and movable to engage either of said pins and permit the arm to be held against movement at every quarter turn, and a pulley at the free end of the arm for engaging a line.

DANIEL E. DAVISON.
